(57) CLAIM

The ornamental design for a sanitizer dispenser, as shown and described.

DESCRIPTION

FIG. 1 is a perspective view of my new sanitizer dispenser taken from a point in front, above and to a right side thereof, with a cartridge door of my new sanitizer dispenser shown in an open position for inserting a chemical cartridge into the receptacle of the sanitizer dispenser. The dashed line showing of a chemical cartridge is for illustrative purposes only, and does not form a part of the claim of my new design.

FIG. 2 is a perspective view of my new sanitizer dispenser taken from a point in front of, above and to a right side thereof showing the cartridge door in a closed position.

FIG. 3 is a planar view of my new sanitizer dispenser taken from a point directly in front of the sanitizer dispenser, with the cartridge door in an open position so that the viewer may view details of the cartridge receptacle.

FIG. 4 is a perspective view taken from a point in front of and to a right side of my new sanitizer dispenser, and particularly showing details of the cartridge receptacle. The remainder of my sanitizer dispenser is broken away for clarity, the broken away portions being shown in FIGS. 1 and 3.

FIG. 5 is a bottom planar view of my new sanitizer dispenser.

FIG. 6 is a top planar view of my new sanitizer dispenser.

FIG. 7 is a left planar view of my new sanitizer dispenser; and,

FIG. 8 is a right planar view of my new sanitizer dispenser.
